SEPARABLE FASTENER

Filed Sept. 13, 1941

Fig. 1.

UNITED STATES PATENT OFFICE

2,316,787

SEPARABLE FASTENER

Sheldon D. Gould, Brooklyn, N. Y.

Application September 13, 1941, Serial No. 410,700

5 Claims. (Cl. 24—205)

This invention relates to slide operated fasteners of the type incorporating interlocking fastener elements.

The increasing use of slide operated fasteners on garments, has caused a search for means to either enhance the appearance of such fasteners or to conceal them. The former trend is, of course, toward a more costly product, while the latter, although attempted, has not achieved commercial recognition because of faulty design and conception.

Covered fasteners of the indicated type have many advantages over the uncovered fasteners. Body hair, loose underclothes, neckties, etc. may not become caught between the fastener elements during manipulation of the slide. This fouling of the fastener has frequently caused destruction of both the fabric so caught and the fastener itself.

Further, exposed fastener elements must necessarily be made of non-oxidizing metal and must be smoothly finished to present a good appearance and have good wearing qualities. Frequently, the elements are made of plastics in an attempt to both match the garment fabric and to obtain the mentioned proper appearance.

With the foregoing in mind, the present invention contemplates an improved slide operated fastener in which the fastener elements are completely covered and thereby permitting the use of inexpensively formed fastener elements.

The invention further contemplates a slide operated fastener in which both sides of the fastener elements are covered and in which the covering means are easily and inexpensively applied with a minimum of sewing.

The foregoing objects, features and advantages of the invention are realized in the structures which are illustrated in the accompanying drawing which forms the basis for the following detailed specification. In the drawing, which exemplifies the invention:

Fig. 1 is a front view, partly broken away, of a fastener incorporating the invention.

Figs. 2 to 6, inclusive, are cross-sectional views of alternate forms of construction, each view showing one of the stringer tapes, a fastener element, and covering means therefor.

Fig. 7 is a cross-sectional view as taken on the plane of the line 7—7 of Fig. 1.

Fig. 8 is an end view of the fastener shown in Fig. 1.

Referring to the drawing in greater detail and with particular reference to Figs. 1, 7 and 8, the fastener is provided in the usual manner with

stringers or tapes 5 and 6. In preceding structures these stringers were each formed with an edge bead and the fastener elements directly clamped upon said edge beads. In accordance with the present invention, the edge beads or cords 7 and 8 of the respective stringers 5 and 6, are completely covered by the middle longitudinal portions 9 and 10 of concealing strips 11 and 12. These encompassing middle portions may be sewed to their respective stringers as shown in the other illustrated forms of the invention. However, as shown in Fig. 7, the fastener elements 15 and 16 may be so formed as to clamp over the portions 9 and 10 of the respective concealing strips 11 and 12 and thereby effectively lock said strips to their respective stringers. The concealing strips 11 and 12 are thus provided with free flap portions which are reversely directed to overlie the fastener elements 15 and 16.

20 The concealing flap portions are disposed at both sides of the fastener and are designated 17 and 18 on one side and 19 and 20 on the other.

It will be noted from the above that the respective pairs of concealing flaps touch each other to effect complete concealment of the elements 15 and 16 to accomplish the purpose of the invention. In order to hold the concealing flaps in place against the fastener elements, it is preferred to stitch them into place as by means 25 of the lines of stitching 13 and 14. Each line of said stitching is arranged to engage the opposite flaps of the same concealing strip and to pass between the related fastener elements as indicated in Fig. 1. These lines of stitching are, of course, placed so that they do not interfere with the interlocking engagement of the fastener elements.

30 The slider 21 is designed to fit over the flaps and to urge the elements into and out of interlocking engagement by contact which is transmitted through the folds in the concealing strips 11 and 12.

The construction of Fig. 7 may be varied in many ways within the concept of the invention. 35 As shown in Fig. 2, the concealing strip 25 may be arranged in folded condition over one longitudinal edge of the stringer 6 and cords 26 applied to each side as shown. This assembly is then held in place as by stitching 27. The fastener elements 28 are so formed as to engage over both cords 26 which serve as effective keying means therefor. As previously described, the concealing strip is provided with concealing flaps 29 for both sides of the elements 28. The cords 26 may, of course, be placed directly against the

stringer 6 and the concealing strip placed thereover. This condition is shown in Fig. 3. The line of stitching 14 may then be applied to hold the flaps against the fastener elements.

If desired, as shown in Fig. 4, the concealing flaps 30 may be formed on strips 31 which have embedded cords 32 and which are applied to both faces of the stringer 6. The elements 33 are applied over the enlarged beads 34 formed in the strips 31 by the cords 32.

In the modification of Fig. 5, the stringer may comprise two tapes 35 which are wider than in the previously described forms and which are placed in back to back relation as shown. The excess of width of each tape is folded over a cord 36 and a line of stitching 37 applied. This forms beads similar to the beads 34 of Fig. 4 and provides concealing flaps 38 for the fastener elements 39.

Certain of the above structures may be combined. For instance, as shown in Fig. 6 the stringer 35 of Fig. 5 may be combined with the tape 31 of Fig. 4 and the fastener element 40 applied as before.

In each of the forms of the invention above described, concealing flaps on both sides of the fastener elements are provided and means for securely anchoring said elements are incorporated in said structures. It will be noted that a sturdy, long-wearing structure is formed wherein the fastener elements may serve to lock the concealing strip or a concealed line of stitching employed for this purpose.

In keeping with the purposes of the invention in providing a neat, concealed fastener, the closed end thereof may be provided with a placket 41 which is substantially U-shaped and has doubled back bifurcated leg portions 42 engaged behind the beads such as 9, 10, 31, 36, etc. The concealing flaps also cover this placket which is thus rendered invisible to the observer.

At the other end of the fastener there may be provided the usual end abutment stop member. Where separation of the fastener ends is desired, the structure shown in Figs. 1 and 8 may be employed. As shown in these figures, a bottom stop 43 may be permanently clamped over the concealing strip 8, the concealing flaps 17 and 18, and a hollow pin 44. The slider 21 abuts this end stop to prevent disassociation thereof from the fastener. The stop member 43 is formed with a seat for receiving the pin 45 of the other fastener tape, said seat being formed sufficiently large to accommodate the concealing flaps 18 and 20 which cover said pin 45. This arrangement makes for easy manipulation of the parts at this point and it will be noted that the concealing flaps overlie and conceal the pins 44 and 45.

It is obvious from the foregoing that the in-

vention may be practiced in many ways within the spirit and scope thereof as claimed. The various structures which are illustrated are intended as by way of example and the language employed in the specification is not intended to limit the scope of said claims.

What I claim as new and desire to secure by Letters Patent, is:

1. A slide operated fastener comprising a supporting tape, a cord disposed adjacent a longitudinal edge of said tape, concealing means comprising a strip folded over said cord and the adjacent portion of said tape and a single line of stitching securing said concealing means to said tape to provide a pair of concealing flaps, said flaps comprising laterally opposed portions of said concealing means.

2. A slide operated fastener comprising a supporting tape, a strip folded over one longitudinal edge of said tape and secured in said folded condition by a single line of stitching to said tape, a plurality of fastener elements clamped to the fold of said strip, lateral longitudinal extensions on said folded strip and beyond said line of stitching, said extensions being folded along said line of stitching to form concealing flaps for said fastener elements, and a line of stitching engaging both concealing flaps and passing between the fastener elements therebetween.

3. A slide operated fastener comprising a supporting tape, a strip folded over one longitudinal edge of said tape, a pair of cords one on each side of said folded strip, a single line of stitching securing said tape, folded strip, and cords together, a plurality of fastener elements engaged with said cords and said folded strip and clamped thereon, and opposed flaps integrally formed on said strip, said flaps being folded along said line of stitching to form concealing means for said fastener elements, and a line of stitching engaging both concealing flaps and passing between the fastener elements therebetween.

4. A stringer for slide fastener elements comprising a tape, a strip folded over one longitudinal edge of said tape and stitched thereto, said strip having integrally formed opposed flaps arranged to conceal fastener elements mounted on said stringer.

5. A slide operated fastener comprising a pair of stringer tapes, a concealing strip mounted on the inner longitudinal edge of each tape, a plurality of fastener elements engaged with said strips and mounted on said tapes, top and bottom stops on said fastener, and concealing means for said elements and said top and bottom stops, said concealing means comprising lateral folded portions of each concealing strip.
